Peter Benoit, Alexandria, Ontario, Canada

Application April 5, 1944, Serial No. 113,157

Term of patent 7 years

(Cl. D72—1)

To all whom it may concern:

Be it known that I, Peter Benoit, a citizen of the Dominion of Canada, residing at Alexandria, in the county of Glengarry, in the Province of Ontario, Dominion of Canada, have invented a new, original, and ornamental Design for a Combined Direction Indicating Signal and Switch, of which the following is a specification, reference being had to the accompanying drawing, forming a part thereof.

In the drawing:

Figure 1 is a front perspective view of a combined direction indicating signal and switch showing my new design.

Figure 2 is a top plan view; and

Figure 3 is a rear elevational view thereof.

I claim:

The ornamental design for a combined direction indicating signal and switch, as shown.

PETER BENOIT.
